(57) **CLAIM**

The ornamental design for a sanitization device, as shown and described.

DESCRIPTION

FIG. 1 is a right side and top perspective view of a sanitization device, showing our new design;
FIG. 2 is a left side and top perspective view thereof;
FIG. 3 is a right side and bottom perspective view thereof;
FIG. 4 is a left side and bottom perspective view thereof;
FIG. 5 is a top plan view thereof;
FIG. 6 is a bottom plan view thereof;
FIG. 7 is a front elevation view thereof;
FIG. 8 is a rear elevation view thereof;
FIG. 9 is a right side elevation view thereof; and,
FIG. 10 is a left side elevation view thereof.
The broken lines illustrate portions of the sanitization device that form no part of the claimed design.
